FAUCET

John Harry Gustafsson, Bromolla, Sweden, assignor to
Ifo AB, Bromolla, Sweden

Filed July 15, 1974, Ser. No. 488,692

Claims priority, application Sweden Jan. 15, 1974

Term of patent 14 years

Int. Cl. D23—01

U.S. Cl. D23—25

FIG. 1 is a front perspective view of a faucet embodying my new design;

FIG. 2 is a rear elevational view thereof;

FIG. 3 is a side elevational view thereof; and

FIG. 4 is a top plan view thereof.

I claim:

The ornamental design for a faucet, as shown.
